UNITED STATES PATENT OFFICE

2,131,863

SKI POLE

Andrew S. Wright, Springfield, Mass.

Application December 30, 1936, Serial No. 118,218

1 Claim. (Cl. 280—11.37)

This invention relates to improvements in skiing equipment and is directed more particularly to the provision of an improved ski-pole.

Ski-poles of usual form comprise a longitudinal pole member having a more or less pointed lower end part for piercing the snow and a ring member spaced from but adjacent the lower end for preventing the pole from digging too deep into the snow. This invention is particularly concerned 10 with the construction of this ring member.

It is one of the principal objects of the invention to provide a ski-pole of novel form which is easy and economical to manufacture and which is at the same time efficient in operation and 15 adapted to withstand considerable abuse. The construction is such that the pole is relatively light in weight, as is desirable, yet it is sturdy and strong.

As particular features of this invention the 20 main body of the ring member is formed from a single piece of strong yet bendable material which is bent into the form of a ring so as to have opposite ends in adjacency and means is provided to firmly and securely hold these ends together. 25 As will appear, this means includes a novel sleeve member which is not only relatively inexpensive but which adapts itself to ready assembling of the parts.

It is usual to form these ring members from 30 lengths of some tough yet light-weight material, such as reed or some other bamboo-like material. While such materials have many desirable advantages and are, therefore, popularly used, they have certain characteristics which cause manu- 35 facturing difficulties and it is an object of this invention to overcome these difficulties.

Various other objects and advantages of the invention will become more apparent after a reading of the following description, reference being had to the accompanying drawing wherein:

Fig. 1 is a side elevational view of a ski-pole embodying the features of the invention;

Fig. 2 is a plan view of a ring-forming member of the invention;

Fig. 3 is a plan view of a sleeve member of the invention;

Fig. 4 is a plan view of the ring-forming parts in assembled relation; and

Fig. 5 is a partial plan view showing a modified 50 form of ring member.

Referring now to the drawing more in detail, the invention will be fully described.

In Fig. 1 there is shown a longitudinal member 2 which commonly consists of a bamboo rod or 55 some other relatively rigid but light-weight ma-

terial. What may be called a handle, in the form of a strap 4, is shown suitably attached to the upper part of the longitudinal member and this commonly is formed of leather or some other similar material.

It is usual to provide a metallic sleeve 5 around the lower end portion of the longitudinal member 2 and then to this may be secured in some way a pointed spike part 6, as shown. The sleeve 5 lends strength and rigidity to the pole, while 10 the spike is for piercing the skiing surface.

In Fig. 2 there is shown a ring-forming member 10 which consists of a rod-like length 8 of some bendable material, such as reed, bamboo, or the like. The rod 8 is usually substantially 15 circular in cross section and it is bent so as to bring its opposite end portions 9 into adjacency.

It was mentioned above that there were certain characteristics commonly found in these ring-forming members which presented manufacturing difficulties. That is to say, reeds or other bamboo-like material have many joints and any given length thereof invariably has its opposite ends of different diameters.

Thus, it will be appreciated, when the rods 8 25 are bent into ring-forming position, the adjacent ends thereof, being of different diameters, do not neatly come together and are only secured together with difficulty. That is to say, one end will sometimes be as much as twice as great in 30 diameter as the other end of the rod so that, it is obvious, it is therefore not only difficult to secure them together at all but then only with loss of efficiency.

According to my invention, I provide a sleeve 35 which, as will appear, may vary in form and which is adapted to receive the adjacent end portions 9 of the rod 8. This sleeve, represented by 12 in Fig. 3 is adapted to fit around the end portions of the rod regardless of their diameters 40 and to hold them in adjacency. The end portions 9 may be in abutting or overlapping relation or may be mitred.

According to the preferred form of the invention, the sleeve 12 takes the form of a tubular 45 member formed of some cellulose plastic material, such as cellulose acetate. This material is not only relatively inexpensive and may be easily obtained in tubes of various sizes so as to accommodate the varying diameters of the rods, but 50 it has the further very definite advantage that it may be caused to shrink and snugly embrace an object.

The sleeve receives the end portion 9 which may be in abutting end relation and is softened 55

in some suitable way so that on hardening it shrinks tightly about and snugly embraces the end portions of the member 8 so as to securely hold the said ends together providing a substantially unitary ring structure.

It will be appreciated that while the sleeve 12 may be originally substantially the same diameter throughout its length, it is of such a nature that after softening it shrinks to conform to and snugly embrace the varying diameters of the end portions 9. The sleeve tightly grips the said end portions so as to firmly hold the rod in ring-forming relation. The sleeve 12 has the further advantage of being relatively thin so as not to produce any objectionable projections or bulging on the ring.

The sleeve may be softened before or after assembling with the ring member and this may be done in various ways. For instance, the material 20 is of such a nature that it shrinks when subjected to warm water or the like.

If desired, further means may be provided for securing the sleeve 12 to the ring-forming member. Such means may take the form of tacks or 25 nails 14 which extend through the sleeve 12 and into the end portions 9.

According to a modified form of the invention, the sleeve may be formed of some other relatively thin material in tube form, such as a relatively light-weight metal. This sleeve, indicated by 12', may receive the adjoining end portions of the ring-forming member 8 in the same way as the sleeve 12.

35 The sleeve 12', being relatively thin and more or less collapsible, may have its opposite end portions crimped in some way, as indicated at 15, so as to grip the end portions of the rod tightly. Then, if desired, nails, tacks, or the

like 14' may be provided to more firmly secure the sleeve to the ring-forming member.

Here again the sleeve is relatively thin, light-weight and inexpensive and does not produce any objectionable projections on the ring, but instead 5 conforms to the diameters of the opposite end portions of the ring.

It is desired to point out that the ring 10 is arranged concentrically of the rod 2 adjacent the lower end thereof. Fastening means, preferably in the form of flexible straps 16, are provided to hold the ring in place, and this means is of usual form and does not comprise any part of this invention.

While I have described the invention in great 15 detail and with respect to a preferred form thereof, it is not desired to be limited thereto since many changes and modifications may be made therein without departing from the spirit and scope of the invention. What it is desired 20 to claim and secure by Letters Patent of the United States is:

As a new article of manufacture, a ski-pole of the class described comprising in combination, a longitudinally-extending rod member, a ring 25 member secured thereto concentrically thereof adjacent one end thereof, said ring member consisting of a single length of bamboo material having opposite ends of unequal outside diameters and bent so that said ends are in abutting relation, and a sleeve member extending around the opposite end portions of said length of bamboo material, said sleeve member consisting of a cellulose plastic tube which is normally of uniform diameter throughout its length shrunk about 30 said end portions by application of a solvent of the plastic material so as to conform to the outside diameters thereof.

ANDREW S. WRIGHT.
